UNITED STATES PATENT OFFICE.

PHILIP E. YOUNG, OF FAIRHAVEN, MASSACHUSETTS, ASSIGNOR TO ACUSHNET PROCESS COMPANY OF NEW YORK, INC., A CORPORATION OF NEW YORK.

WASHMILL.

1,267,493.

Specification of Letters Patent. Patented May 28, 1918.

Application filed July 23, 1917. Serial No. 182,188.

To all whom it may concern:

Be it known that I, PHILIP E. YOUNG, of Fairhaven, Massachusetts, have made certain new and useful Improvements in Wash-mills, of which the following is a specification, reference being had to the accompanying drawings, in which—

Figure I is a view of one end of a mill embodying my invention.

10 Fig. II is a view of the opposite end.

Fig. III is a plan view.

Fig. IV is a diagrammatic representation of the operation of the mill.

In preparing crude and reclaimed rubber for use, it is ordinarily necessary to wash the rubber thoroughly before incorporating it into the ultimate compound. My invention relates to a mill to be used for such washing, and I aim to design a mill which will wash rubber more rapidly than has been possible on the mills used heretofore, by putting a sheet of rubber under tension and washing the sheet while under tension.

Referring to the accompanying drawings, 25 2 and 2' are bases which carry fixed blocks 3 and 3' respectively and also blocks 4 and 4' movable by screws 5 and 5'. On bases 2 and 2' are frames 6 and 6', which carry fixed blocks 7 and 7', and blocks 8 and 8' movable by screws 9 and 9'. On the frames 6 and 6' are caps 10 and 10'. Roll A is mounted in blocks 3—3'. Roll B is mounted in blocks 4—4'. Roll C is mounted in blocks 7—7'. Roll D is mounted in blocks 8—8'. Beneath bases 2—2' are bearings 11—11', which carry shaft E. Shaft E has keyed to it a gear E' and a pulley E².

40 Gear E' meshes with gear A' keyed to roll A, and gear A' meshes with gear C' keyed to roll C. Gear C' is larger than gear A', the ratio being about six to five.

On the opposite end of roll A from gear A' is keyed gear A², which meshes with gear B² keyed to roll B. Likewise, on the opposite end of roll C from gear C' is gear C², which meshes with gear D² keyed to roll D. Gear A² is larger than gear B² and gear D² is larger than gear C², the ratio in each case being approximately five to four. From 50 these gear ratios, it is apparent that all four rolls will travel at different speeds, roll B traveling faster than roll A and roll C faster than roll D, and both rolls A and B faster than C and D.

55 Caps 10 and 10' carry between them a

water pipe 12, and frames 6 and 6' carry between them water pipes 13 and 14. The water pipes 12, 13 and 14 are perforated throughout their length so as to direct a flow of water, as shown in Fig. IV.

60 By means of screws 5—5' and 9—9', the rolls are set so as to leave an aperture of about one quarter of an inch between rolls A and B, and C and D. Power is applied to the mill through the pulley E², which is involved in the direction shown in the arrow in Fig. I. This causes the rolls to rotate. The rubber to be washed is placed in a mass in the pocket above and between rolls C and D. Rotation of these rolls causes a sheet of 70 rubber to pass down toward rolls A and B. This sheet is caught between rolls A and B, and inasmuch as rolls A and B travel faster than C or D, the sheet of rubber is put under tension. At the same time, the water from 75 pipe 12 tends to loosen the dirt, and the water from pipes 13 and 14, striking the sheet under tension, washes the dirt from the sheet with great rapidity.

80 As the rubber passes down from between rolls A and B, the operator picks up one end of the sheet and returns it to the mass above and between rolls C and D, so that a continuous sheet is formed, as shown in Fig. IV.

85 Inasmuch as the rubber is fed out from between rolls A and B more rapidly than it is fed from between rolls C and D, the sheet on the outside of the mill will tend to travel less rapidly than the portion of the sheet 90 passing through the mill, and the rubber will tend to collect beneath the mill. To overcome this difficulty (which is a common fault in wash mills) I have provided the idler roll 15, which is carried on the frame 95 16, which in turn is pivoted on the bar 17, carried by the caps 10—10'.

100 Before the continuous sheet is formed, the roll 15 is raised and the end of the sheet is brought up to the pocket between the rolls C and D, as already explained. After the sheet is formed, the idler roll 15 is dropped, so that its weight holds the sheet against roll C. Inasmuch as the weight of roll 15 exerts only a slight pressure on the rubber, the sheet will move upward at the full speed of roll C, which, experience has shown, is faster than the movement of the sheet throughout the rest of the machine. The operator by laying his hand on the roll 15, can 110

control the speed of this roll and thus control the amount of rubber that is fed between the rolls C and D.

When the rubber is completely washed, 5 the sheet is cut and removed in the ordinary, well-known manner.

The screws 5—5' and 9—9' serve two purposes. They not only control the thickness of the sheet that is formed in the mill, but 10 likewise can be used to control the tension placed on the sheet between the two sets of rolls. For example, if screws 5—5' are moved in so that rolls A and B are relatively close together, and screws 9—9' are moved 15 out so that there is a relatively large gap between rolls C and D, so much more rubber will pass between rolls C and D than between rolls A and B for each rotation of these rolls, that, despite the fact that rolls 20 A and B travel faster than rolls C and D, the rubber between these two sets of rolls will not be put under any tension at all. Conversely, if the rolls C and D are set quite close together, and the rolls A and B more 25 widely apart, the tension will be increased.

By thus providing means for adjusting the tension of the sheet between the two sets of rolls, it is possible to have the two sets of rolls travel at substantially the same 30 rate of speed and still keep the sheet under tension. I have found, however, that the relative speeds set forth in this specification are those best adapted for general practice, for with these speed ratios the tension can 35 be adjusted from substantially zero to a point where the sheet of rubber will be broken. It is thus apparent that the speed ratios of the rolls may be greatly varied and that many other changes may be made in the 40 details of constructions without departing from the spirit of my invention.

What I claim is:

1. A mill for washing rubber and the like, comprising two pairs of rolls through which 45 a sheet of rubber is adapted to pass successively, means for causing the rubber to pass more rapidly through the second pair than the first pair so that the rubber may be placed under tension between the two pairs

of rolls, and means for washing the rubber 50 while under such tension.

2. A mill for washing rubber and the like, comprising two pairs of rolls through which a sheet of rubber is adapted to pass successively, means for causing the rubber to pass 55 more rapidly through the second pair than the first pair so that the rubber may be placed under tension between the two pairs of rolls, means for regulating the degree of tension, and means for washing the rubber 60 while under such tension.

3. A mill for washing rubber and the like, comprising two pairs of rolls through which a sheet of rubber is adapted to pass successively, the second pair of rolls being geared 65 to rotate more rapidly than the first pair, and means for washing the rubber intermediate the two pairs of rolls.

4. A mill for washing rubber and the like, comprising a pair of rolls adapted to sheet 70 the rubber, means for placing the sheet of rubber under tension as it leaves said rolls, and means for washing the rubber while under such tension.

5. A mill for washing rubber and the like, 75 comprising two pairs of rolls, the first pair being adapted to sheet the rubber and the second pair to place the sheet under tension as it passes from the first pair, and an idler roll adapted to hold the sheet after passing 80 from the second pair of rolls against one of the rolls of the first pair to return the sheet for further washing.

6. In a rubber mill, the combination of a pair of driven rolls adapted to sheet the 85 rubber, and an idler roll readily movable into and out of contact with the sheet formed thereby and adapted when in contact with such sheet to hold the same against one of said rolls to return the sheet for further 90 treatment, said idler roll being likewise adapted to have its speed of rotation directly under the control of the operator so that the speed with which said sheet of rubber is returned for treatment may be controlled.

PHILIP E. YOUNG
